UNITED STATES PATENT OFFICE.

EDWARD Z. LEWIS, OF EVANSTON, ILLINOIS, ASSIGNOR TO REMINGTON TYPEWRITER COMPANY, OF NEW YORK, N. Y., A CORPORATION OF NEW YORK.

MANIFOLD BILLING ATTACHMENT FOR TYPEWRITING MACHINES.

Application filed March 24, 1924. Serial No. 701,270.

This invention relates to a novel and improved manifold-billing attachment for typewriting machines and consists of the matters hereinafter described and more particularly 5 pointed out in the appended claims. Although shown as an attachment to a marketed typewriting machine, in the present instance the Monarch typewriter, it is to be understood that the invention may be built into 10 or incorporated with typewriting machines as manufactured.

The invention relates more specifically to improvements in an attachment for typewriters of the kind shown in Letters-Patent 15 No. 937,374 heretofore issued to me on October 19, 1909, by means of which a multiform billing sheet, together with a carbon paper or carbon ribbon is wound upon the platen of the machine to make manifold copies at one 20 writing. As will appear, the multiform billing sheet may be of the single sheet type shown in my Patent No. 932,713, August 31, 1909, or it may be of the folded sheet type shown in my Patent No. 1,017,798, February 25 13, 1912, in which the sheet has all the forms printed on one side, (in the folded sheet type, on the similarly faced sides of the two sections of the sheet) with the first form, at the top of the sheet, of a height equal to the 30 length of the circumference of the platen and with the downwardly succeeding forms progressively increased in vertical dimensions, both as to height and as to the spacing between the horizontal lines of the forms. 35 The carbon paper or ribbon is wound with its copying surface against the printed face of the sheet (a carbon face being preferably provided on the rear face of the top section in the case of the folded sheet) and the original typewritten matter is produced on the bottom form of the billing sheet, which will 40 constitute the outermost winding of the sheet upon the platen.

The object of the invention is to provide 45 novel and improved features in the attachment by means of which the billing sheet may be automatically fed to and suitably engaged with the platen so that it may be rapidly wound upon the platen with the carbon 50 ribbon the required number of revolutions; and the sheet may be automatically ejected after it has been written upon, without any handling or guiding of the sheet by the operator. It is of course to be understood that 55 other styles or kinds of work sheets besides

those illustrated and described herein may be employed with the present invention.

This and other objects and advantages of the invention will be more easily pointed out and recognized as I proceed with my 60 specification.

In the drawings:—

Fig. 1 is a view representing a typewriter, in front elevation, on a table (in vertical section) with my improved attachment in 65 operative connection to the typewriter.

Fig. 2 is a top plan view, on a larger scale, of the typewriter with the parts of the attachment which are directly connected thereto.

Fig. 3 is a longitudinal central section 70 through one of the tension rolls of the attachment.

Fig. 4 is a side elevation on a larger scale 75 of the parts shown in Fig. 2, as viewed from the right hand side of Fig. 2.

Figs. 5 and 6 are views, on the scale of Fig. 4, representing like vertical sections through Fig. 2 in a plane indicated by the line 5—5 at different stages of the winding 80 movement of the platen.

Figs. 7 and 8 represent plan views of the multiform billing sheet,—one, Fig. 7, a single sheet type, and the other, Fig. 8, a double or folded sheet type.

Fig. 9 is a transverse sectional view of the sheet shown in Fig. 8 in a plane indicated by the line 9—9 of Fig. 8.

Fig. 10 is a view similar to Fig. 5 showing a somewhat modified construction for delivering the billing sheets to the platen.

Fig. 11 shows the same parts as Fig. 10 with the parts in a somewhat different relation.

Fig. 12 is a front elevation of the guide 95 ribbons in the neighborhood of the platen.

Fig. 13 is a fragmentary view to be explained later.

Fig. 14 is an enlarged detail view of parts shown at the right of Fig. 1.

Referring now to that embodiment of the invention illustrated in the drawings:—10 indicates a typewriter of familiar construction, that is the Monarch typewriter, provided with the improved manifold billing attachment; and 11 indicates a table supporting the same. 12 indicates the main frame of the typewriter; 13, the paper carriage, which has end plates 14, 15; and 16 indicates the platen. The platen has in its 110

surface a longitudinal groove 17 and a removable or hinged rod 18 by means of which the end of the carbon ribbon or reproducing sheet 19 is gripped and connected to the surface of the platen.

20 indicates the tension or spring roller upon which the carbon ribbon is normally wound. In the present instance, said tension roller is mounted on the paper carriage 10 13 vertically above the platen. Said roller constitutes a rewind roller for the carbon ribbon after the typewriter has been operated upon the billing sheet and maintains a tension on the carbon sheet while it is being wound with the billing sheet upon the platen, thus insuring a smooth winding about the platen.

Back of the tension roller 20 is a second roller 21. This is also a tension roller and 20 has wound upon it two laterally spaced guide tapes 22, which have their ends attached to the platen 16 by means of the groove and rod 17, 18, as in the case of the carbon ribbon 19. The guide tapes 22 are 25 spaced in such manner that they will engage the billing sheet near its lateral margins and beyond the space on the sheet to be written upon. As shown in Fig. 3, said tapes are wound upon spools 22^a, which are 30 fixed on or integral with the tension roller 21, thus maintaining the tapes in the desired spaced relation. The tension roller 21 is mounted on the paper carriage 13. The tension roller 21 is hollow and contains a 35 coiled spring 21^x which tends to turn it on the axle 21^y. The tension roller 20 is provided with a similar turning spring (not shown).

40 The tension roller 20 for the carbon ribbon is preferably provided with laterally spaced flanges 20^a, 20^a (see Fig. 2) to engage the lateral edges of the carbon ribbon and guide the ribbon laterally in its winding and unwinding movement upon the platen. 45 One of said flanges is removable.

50 The plane of the carbon ribbon 19 and the plane of the tapes 22, in their paths from their respective tension rollers to the platen, meet in a sharp angle at the surface of the platen and it is into the apex of this angle that the end of the billing sheet must be delivered and held to the platen in order that the billing sheet and carbon ribbon may be 55 operatively wound together upon the platen in the required manner.

It will be convenient here to describe the 60 multiform billing sheet itself. As shown in Fig. 7, it is a single sheet 23, with four forms 24, 25, 26, 27,—24 being the top form. The sheet is upside down in position as it appears when it is fed to the platen and looked at from the rear of the platen. The forms are of vertically increased dimensions and spaced as heretofore so that each 65 form may completely encircle the platen

when the sheet is wound around the platen with the carbon ribbon 19 and tapes 22. At the top 24^a of the sheet is provided an extension or short flap 24^b which is folded back towards the rear face of the sheet.

70 A stack 23^x of the sheets 23 (see Fig. 1) is supported in any convenient manner above the tension rolls 20, 21 in position for the top sheet of the stack to be fed into the angle between the carbon ribbon 19 and the tapes 22. As shown, a board 28 is supported in a plane inclined from the table 11. Any suitable supports 28^a connect the board to the table. The stack of sheets 23^x are held on the board by a pin 28^b, fixed at the top of the board and projecting outwardly therefrom (see 75 Figs. 1 and 13) to engage in a hole 28^y formed at the bottom of the sheet. (See Figs. 7 and 8.) The pin 28^b has a knife 80 edge 28^d at the top, so that although the pin will act to support the stack of sheets 23^x, a slight, but positive downward pull will act to withdraw a sheet from the stack without disturbing the rest of the sheets in 85 the stack. The board preferably has side flanges 28^c to engage and guide the edges of the sheets on their way towards the platen.

90 In front of the board is supported a reciprocating plunger 29, which is adapted to 95 deliver the sheets in succession from the stack to the platen. Said plunger comprises a cross head 30 slidably mounted on vertical guide bars 31, 31; and laterally spaced 100 depending fingers 32, 32. The guide bars 31 are attached at their top ends to a yoke 33 which is connected to the flanges 28^c of the board 28. Said guide bars carry at their bottom ends a transverse bar 34, which acts 105 as a stop to limit the downward movement of the cross head 30.

110 The sheets 23 are arranged in the stack with their flaps or engaging devices 24^b towards the front and in a position somewhat below the topmost position of the bottom ends of the fingers 32, and in the path to be followed by said fingers. As the fingers descend, their ends engage in the angle between the flap 24^b and the body of 115 the top sheet 23 of the stack, and carry said sheet downward towards the platen and into the angle between the carbon ribbon 19 and the tapes 22.

120 While the fingers 32, 32 deliver the top end of the sheet 23 into the angular space between the carbon ribbon and the tapes as stated, it is generally essential in order that the said sheet end will be gripped between the tapes and carbon ribbon and wound 125 properly with them about the platen, for an additional mechanism to be employed. This is a device to, as it were, "kick in" said sheet end substantially at the instant that the platen begins its rotary winding movement. In the embodiment of the invention 130

illustrated herein, this device consists of a sleeve 35 (see Figs. 3, 5 and 6) fixed on the tension roller 21 (which carries the tapes 22) midway between the spools 22^a on which 5 said tapes are wound. Said sleeve is preferably made of yielding material, as for example, rubber, and is elliptical in cross-section. It is fixed on the roller with the periphery of the shorter axis next the path 10 to be followed by a billing sheet on its way to the platen, as shown in full lines in Fig. 5. When the platen is operated to wind the carbon ribbon and tapes upon it, the sleeve 35, rotating with the unwinding of the tapes 15 22, from their spools 22^a will bring a peripheral part of its greater axis into frictional engagement with the face of the sheet 23 next to it and act to carry down or "kick in" the sheet 23, (as shown in dotted lines 20 in Fig. 5) so that the end of said sheet will be engaged positively in the sharp angle between the tapes 22 and the carbon ribbon 19 and will thus be wound with the carbon ribbon and tapes upon the platen. 25 Any suitable mechanism, hand operated or power driven, may be used to rotate the platen the required number of turns and to reciprocate the fingers 32 in suitable timed relation. As shown, the mechanism is operated 30 by a treadle 36 (see Fig. 1) pivoted at 37 to the floor below the typewriter and having pivotally connected to it at a point remote from the pivotal point 37, a vertical link 38. Said link extends up through the 35 table 11 and is above the table operatively connected to a bell crank lever 39 pivoted at 40 to a standard 41 mounted on the table. One arm 39^a of the lever 39 (to which the link 38 is connected) carries a one-way pawl 42 adapted to engage a pin 43^a on a vertically movable rod 43, (with a suitable guide bearing in the table 11) which is connected to a lever 44 fulcrumed at 44^a to a laterally extending bracket arm 44^b fixed to the 45 yoke 33. The other end of the lever 44 is pivotally connected to a short link 45 which is in turn pivotally connected to the cross head 30. A coiled tension spring 44^c normally holds the lever 44 in position so that the cross head 30 and the fingers 32 carried thereby are in their uppermost position. 50 The platen is driven by speed increasing gearing comprising a large gear 46 mounted on the end plate 14 of the paper carriage (see Fig. 4), an intermediate idle gear 47 and a pinion 48 on the proximate end of the platen shaft. The large gear 46 has a stud 46^a which is connected by a universal joint 46^b to a horizontal telescopic shaft 49 which extends over towards the standard 41. 55 50 indicates a small bevel pinion on the end of said shaft which is engaged by a larger bevel pinion 51 located in a plane at right angles to the plane of the pinion 50 and connected by suitable clutch or ratchet mechanism 52 (see Fig. 14) to a spur gear 53 located in a parallel plane adjacent to and on the same axis as the bevel gear 51. The arm 39^b of the bell crank lever 39 carries a segmental spur gear 54 which is adapted to engage the spur gear 53. The treadle 36 is normally retained in its upper position by means of a coiled tension spring 55 connecting it with the table 11. 60 The operation of this mechanism is as follows: When the treadle 36 is depressed, it swings the bell crank lever 39 upon its axis 40 in the direction of the arrow. In the first part of the movement of the bell crank lever 39, the one-way pawl 42 carried by the arm 39^a acts through the pin 43^a to pull down the rod 43 and swing the lever 44 (against the action of the spring 44^c) to depress the crosshead 30 with its fingers 32, which feed one of the sheets 23 to the platen 16 as heretofore described. The parts are so designed that when the fingers 32 have delivered a sheet to the platen, the one-way pawl 42 slips by the pin 43^a on the rod 43 and releases said rod, thus permitting the lever 44 to return to its normal position and restore the fingers 32 to their uppermost position. Just about the time the pin 43^a is thus disengaged, the segmental gear 54 engages the spur gear 53, and in the second part of the movement of the bell crank lever 39, the spur gear 53 and the bevel gear 51 are rotated (in the direction of the arrow) thereby rapidly rotating the platen 16 through the described gear trains. The downward movement of the treadle 36 is arrested when the platen has been rotated a predetermined number of times—such arresting means as shown, consisting of a pin 56 on the standard 41 to be engaged by the arm 39^a of the bell crank 39. Upon release of the treadle the bell crank lever is returned to its normal position—the segmental gear 54 in its return movement in engagement with the spur gear 53, being inoperative to rotate the bevel pinion 51 in the reverse direction due to the clutch 52. 70 At the left hand end of the platen 16 is provided a stud shaft 63 and knurled knob 64 for rotating the platen for line spacing and the like. The usual line space mechanism (not shown) for turning the platen step-by-step is provided. A pawl and ratchet 65, 66 are provided adjacent this knob between the frame and the end of the platen to hold the platen against the spring tension exerted by the carbon ribbon 19 and the tapes 22, 22. Thus, after the outer bill form has been written upon, the release of the platen by the disengagement of the pawl 65 from the ratchet 66, permits the tension of the carbon ribbon 19 and the tapes 22 to operate to unwind the carbon ribbon, tapes and the billing sheet from the platen. 75 This is brought about very rapidly with 80 85 90 95 100 105 110 115 120 125 130

the result that the sheet is ejected. A release arm 67 of any familiar construction is provided adjacent the pawl and ratchet 65, 66 for disengaging the platen as described.

As will be manifest, it will be necessary for the operator to have the release arm 67 in position such that the last named pawl and ratchet 65, 66 are disengaged when the treadle 36 is depressed for feeding and delivering a sheet to the platen and rotating the platen to wind the sheet and carbon ribbon and tapes upon the platen. This, because the rotation of the platen is resisted by the tension of the carbon ribbon and of the tapes and it is, therefore, desirable to have no other braking action to impede the rotation of the platen. When the platen is rotated the required number of times to bring the bottom form on the billing sheet into writing position, the release arm 67 will be let go and the feet may then be lifted from the treadle 36, after which the type-writing operation may be proceeded with in the normal manner. As will be understood, the number of revolutions will depend upon the number of forms on a billing sheet, which in the present case is shown to be four. Where a smaller or greater number of forms are used on a billing sheet, the location of the arresting pin 56 on the standard 41 and the arcuate length of the segmental gear 54 will be modified accordingly.

35 In Fig. 8 I have shown a folding form of
billling sheet 70. In this case each section
71, 72 of the billling sheet is provided with
a set of forms, four in number, as in the
case of the single sheet shown in Fig. 7, and
40 each section is also provided at its top end
with a flap 73, 74 respectively. The one
section 71 is also provided with a carbon
face 75 on the side reverse to that on which
the forms are printed, so that what is writ-
45 ten on a form on one section will be repro-
duced on the similarly placed form on the
other section. Thus, manifestly eight forms
may be written at one operation in the case
of such a billling sheet as compared to four
50 in the case of the one shown in Fig. 7. In
arranging the sheets for delivery to the
platen they are stacked and operated upon
in the same way as in the case of the single
sheet.

55 sheet. In order that the sheet may be guided in its ejection from the platen upon the actuation of the release arm 67, I preferably provide a guide or throw-off plate 77 (see Fig. 1). Said guide plate is attached to the stop 34 at the bottom ends of the guide members 31 for the crosshead carrying the fingers 32 and is located, as indicated in Fig. 6, so that it will project into the path of the sheet on its way to the platen. This guide plate is made flexible, so that in the downward

movement of the sheet it will be pushed aside and will not interfere with the delivery of the sheet to the platen. Upon the ejection of the sheet, however, the guide plate will strike the upwardly moving end 70 of the sheet and guide the sheet, towards the front or towards the back of the machine, depending upon which way it is adjusted (towards the front as shown in Fig. 6) and thus insure the discharge of the sheet 75 towards the point desired.

As will be understood, the specific form of billing sheet with the folded flap at its top end is merely one example of a billing sheet provided with means adapted to contact with the specific form of delivery finger illustrated and described herein as one exemplification of such finger. No claim herein is made to the form of billing sheet illustrated, which is claimed specifically in another application relating thereto. 80 85

In Figs. 10, 11 and 12 I have shown a modified form of feeding and delivering means for the sheets. Instead of the fingers 32 and the "kick-in" device 35, I provide a thin plate 80 which is attached to the tapes 22^x and extends transversely between them. The tension roller 21^x for the tapes in this case is placed somewhat farther away from the platen and the sheet support 28^x is placed so that the top ends of the sheets provided with the flaps 24^b extend down below the tension roller 21^x. In addition, the sheets are so formed in this case that the flaps are turned towards the rear instead of towards the front as in the other case,—that is to say, the flaps are turned towards the printed face of the sheet, instead of towards the unprinted face as in the first case.

printed face as in the first case. 105
When the tapes are fully wound upon the tension roller, the plate or blade 80 is located in a position somewhat above the ends of the billing sheets. When the platen 16^x is rotated to wind the carbon ribbon and tapes thereon, the blade 80 carried by the tapes, on the way towards the platen engages the flap 24^b of the lowermost sheet in the stack and carries the sheet towards the platen where it is interwound between the tapes and the carbon ribbon, as shown in Fig. 11. 110 The plate 80 is transversely curved to conform to the curvature of the platen so that when it engages the platen it will not make a bump or projection on said platen. 115

As will be manifest from a consideration of Figs. 10 and 11, it is necessary in designing the platen winding mechanism, to provide that the platen be wound, in addition to the number of times required for the forms on the billing sheet, through an additional 120 arc equal to the distance of the end of the billing sheet from the platen when the sheet is held on its support prior to the feeding and delivering of the sheet to the platen. 125 It will also be manifest that the mechanism 130

required for operating the crosshead 30 and fingers 32, namely, the rod 43 and the lever 44, will be omitted when this type of sheet feeding and delivering means is used.

5. In order to accommodate the support for the sheets to sheets with different numbers of forms thereon, it is preferable to provide a plurality of holes or openings 28^a (see Fig. 10) in the board 28^a to receive the sheet supporting pin 28^b. The distance between these will be equal to the distance between the forms on a billing sheet so that the ends of the sheet next to the end of the platen will always be in a predetermined position with reference to the feeding and delivering mechanism.

When a delivery device such as that shown in Figs. 10 to 12 inclusive, is used, the weight of the sheets in the stack above the bottom sheet will provide pressure against which the delivery device 80 may operate when gripping a bill and carrying it on its way to the platen. Where the stack of sheets is supported as in the case of the delivery device shown in Figs. 1 to 9 inclusive, and the top sheet is engaged by the delivery fingers, it is preferred to provide a pressure to act upon the bottom of the stack so as to always hold the top sheet in the path of the delivery finger. This pressure is conveniently provided as shown in Fig. 1 by means of a block or follower 90 supported in suitable guideways for movement at right angles to the stack of sheets through a hole 91 in the board 28 near the bottom end of said board, and yieldingly held against the bottom of the stack by means of a coil spring 92 engaged against the back of the follower or block 90. The yielding pressure for the block is provided by means of a coil spring engaged against its back and secured at its ends to short bell crank levers 93, attached to the sides of the board. The arms 93^a to which the ends of said springs are attached are in the path of laterally extending rods 94 carried by the cross head 30. Thus, when the plunger carrying the fingers has passed to its lowermost position, the cross head 30 in bringing the fingers to this position has caused the rods 94 to strike the arms 93^a of the bell crank levers 93 and release the tension of the spring, as they do so swinging the other arms 93^b of the bell crank levers into the path of the pins 94 on the cross head. Thus, when the cross head returns to its uppermost position the second pair of arms 93^b are struck and the spring is made to again engage the back of the block and hold it to push the stack of sheets upwardly towards the path of the fingers.

I claim as my invention:

1. In a billing attachment for typewriters, a platen, a carbon ribbon and guide tapes meeting in a common line in the periphery of the platen and connected thereto, and

means for automatically delivering an end of a billing sheet to said platen between the carbon ribbon and tapes.

2. In a billing attachment for typewriters, a platen, a carbon ribbon and guide tapes meeting in a common line in the periphery of the platen and connected thereto, means for supporting a stack of billing sheets, and a device for automatically removing a billing sheet from said stack and delivering an end of said sheet to said platen between the carbon ribbon and tapes.

3. In a billing attachment for typewriters, a platen, a carbon ribbon and guide tapes meeting in a common line in the periphery of the platen, and connected thereto, means for supporting a stack of billing sheets in such manner as to be removable one at a time, and a device for removing a billing sheet from said stack and delivering an end of said sheet to said platen between the carbon ribbon and tapes.

4. In a billing attachment for typewriters, a platen, a carbon ribbon and guide tapes meeting in a common line in the periphery of the platen and connected thereto, a device for automatically delivering an end of a billing sheet to said platen between the carbon ribbon and tapes, and means acting upon the rotation of the platen to "kick in" said sheet end to insure interwinding with said carbon ribbon and tapes.

5. In a billing attachment for typewriters, a platen, a carbon ribbon and guide tapes meeting in a common line in the periphery of the platen and connected thereto, means for supporting a stack of billing sheets, a finger for feeding the sheets, one by one from said stack, and delivering the sheet end to said platen between the carbon ribbon and guide tapes, and a device acting upon the rotation of the platen to "kick in" said sheet end to insure interwinding with said carbon ribbon and tapes.

6. In a billing attachment for typewriters, a platen, a carbon ribbon and guide tapes meeting in a common line in the periphery of the platen and connected thereto, means for supporting a stack of billing sheets, for delivery one at a time, a finger for delivering a sheet from said stack to the platen between the carbon ribbon and tapes, a device acting upon the rotation of the platen to "kick in" said sheet to insure its interwinding with said carbon ribbon and tapes, and means for operating said finger for rotating said platen in proper timed relation.

7. In a billing attachment for typewriters, a platen, a carbon ribbon and guide tapes meeting in a common line in the periphery of the platen and connected thereto, said carbon ribbon and guide tapes being under tension, means for automatically delivering an end of a billing sheet to said

platen between the carbon ribbon and tapes, means for rotating said platen a predetermined number of times, said means being inoperative in the further rotation of said platen in the operation of the typewriter, and normally locked releasing means for holding said platen against the tension of said carbon ribbon and tapes.

8. In a billing attachment for typewriters, including a platen, carbon ribbon and guide tapes attached to the platen and a finger for delivering an end of a billing sheet to said platen between the carbon ribbon and tapes, means for rotating the platen including speed increasing gearing, and a common prime mover adapted for actuating said delivery finger and the platen rotating means in proper timed relation.

9. In a billing attachment for typewriters, including a platen, carbon ribbon and guide tapes attached to the platen, a finger for delivering an end of a billing sheet to said platen between the carbon ribbon and tapes, a "kick in" device acting upon the rotation of the platen to insure the interwinding of the sheet with the carbon ribbon, means for rotating the platen including speed increasing gearing, and a common prime mover adapted for actuating said delivery finger and the platen rotating means in proper timed relation.

10. In a billing attachment for typewriters, in combination with the platen, and means, including speed increasing gearing, for rotating the platen a predetermined number of complete revolutions at a single operation, said means being inoperative after said platen has been thus rotated and permitting independent further rotation of the platen in both directions.

11. In a billing attachment for typewriters, a platen, a carbon ribbon and guide tapes meeting in a common line in the periphery of the platen and connected thereto, and means for supporting a stack of billing sheets at a point remote from the platen, said means permitting the delivery of the sheets one at a time and said means including guides adapted to direct the lateral margins of the sheet on its path to the platen.

12. In a billing attachment for typewriters, a platen, a carbon ribbon attached to the platen along a longitudinal line of its periphery, and means for automatically delivering an end of a billing sheet to said platen to be interwound with the carbon ribbon upon the rotation of said platen.

13. In a billing attachment for typewriters, a platen, a carbon ribbon connected to said platen along a longitudinal line of its periphery, means for supporting a stack of billing sheets, and a device for automatically removing a billing sheet from said stack and delivering an end of said sheet to

said platen in a line parallel to the line of attachment of said ribbon.

14. In a billing attachment for typewriters, a platen, a carbon ribbon attached to said platen along a longitudinal line of its periphery, means for supporting a stack of billing sheets in such manner as to be releasable one at a time, and a device for removing a billing sheet from said stack and delivering an end of said sheet to said platen with said end parallel to the line of attachment of the ribbon to the platen.

15. In a billing attachment for typewriters, a platen, a carbon ribbon under tension connecting said platen along a longitudinal line of its periphery, means for delivering a billing sheet to said platen with the end of said billing sheet parallel to the line of attachment of said carbon sheet, and means for rotating the platen a predetermined number of times to interwind said billing sheet with said carbon ribbon.

16. In a billing attachment for typewriters, a platen, a carbon ribbon under tension connecting said platen along a longitudinal line of its periphery, devices for guiding the lateral edges of the carbon ribbon on its path to said platen, means for delivering a billing sheet to said platen with the end of said billing sheet parallel to the line of attachment of said carbon sheet, and means for rotating the platen a predetermined number of times to interwind said billing sheet with said carbon ribbon.

17. In a billing attachment for typewriters, a platen, a carbon ribbon under tension connecting said platen along a longitudinal line of its periphery, means for delivering a billing sheet to said platen with the end of said billing sheet parallel to the line of attachment of said carbon sheet, means for rotating the platen a predetermined number of times to interwind said billing sheet with said carbon ribbon, and means for directing the billing sheet in a predetermined direction when the platen is wound in the reverse direction to discharge said billing sheet.

18. In a billing attachment for typewriters, a platen, a long ribbon connected thereto at one end along a longitudinal line in the periphery of the platen and adapted to be wound round the platen a number of times with a billing sheet consisting of a number of forms printed one above the other, and means for automatically delivering the end of said billing sheet to a line on the platen parallel to the line along which the end of the carbon ribbon is attached.

19. In a billing attachment for typewriters, a platen, a long ribbon connected thereto along a longitudinal line in the periphery of the platen, and adapted to be wound round the platen a number of times,

means for holding in position a stack of billing sheets, and means for releasing said sheets one at a time as the sheet is about to be delivered to the platen.

- 5 20. In a billing attachment for typewriters, a platen, a long ribbon connected thereto along a longitudinal line in the periphery of the platen, and adapted to be wound round the platen a number of times, 70
 10 means for supporting a stack of billing sheets, means for releasing sheets from the stack one sheet at a time, and means including guides adapted to direct the lateral margins of the sheet on its path to the 75
 15 platen.

21. In a billing attachment for typewriters, a platen, a long ribbon connected thereto along a longitudinal line in the periphery of the platen and adapted to be 80
 20 wound round the platen a number of times, means for supporting a stack of billing sheets consisting of a number of bills printed one above the other, on the sheet, 85
 25 means for releasing from the stack, one sheet at a time, a device for delivering the end of the sheet to a line on the surface of the platen, and means, acting simultaneously with the starting of the rotation of the 90
 30 platen, to kick in the said sheet to insure interwinding with said carbon ribbon as it winds around the platen.

22. In a billing attachment for typewriters, a platen, a long ribbon connected thereto at one end along a longitudinal line 95
 35 on its face and adapted to be wound round the platen a number of times, a billing sheet, and means for automatically delivering one end of the billing sheet to the said longitudinal line on the face of the platen, means for interwinding the billing sheet with said carbon ribbon, and means acting when the 100
 40 billing sheet is being unwound from the platen for guiding the other end of the billing sheet in a path away from the platen.

- 45 23. In a billing attachment for typewriters, a platen, a ribbon connected thereto at one end along a longitudinal line on its face, means for supporting a stack of 105
 50 billing sheets to be fed one at a time into the attachment, a finger for removing the sheets one by one from the said stack and delivering the end of a sheet to the line on the platen to which the ribbon is attached, and a device acting simultaneously 110
 55 with the rotation of the platen to kick in said sheet and insure interwinding it with the ribbon.

24. In a billing attachment for typewriters, a platen, a long carbon ribbon connected thereto at one end along a longitudinal line on its face, means for rotating the platen a predetermined number of times, a tension roller parallel to the platen to which the other end of the ribbon is attached, a ratchet device for holding the 115
 60
 65

platen against the tension of the ribbon, a device for rotating the platen that ceases to function when a predetermined number of revolutions have been made, said device permitting further rotation of the platen 70
 in operation of the typing of a billing sheet which consists of a row of the same number of bills as the predetermined number of revolutions of the platen, said billing sheet being adapted to be interwound round the 75
 platen with the carbon ribbon.

25. In a billing attachment for typewriters, a platen, a long carbon ribbon connected thereto at one end along a longitudinal line on the face of the platen and 80
 connected at the other end to a tension roller mounted on a frame, said tension roller being parallel to the platen, and having the other end of the ribbon connected thereto, flange guides around the roller adapted 85
 to direct the lateral margins of the carbon ribbon when rewound on the roller, one of said flange guides being removable when renewing the carbon ribbon.

26. In a billing attachment for typewriters, a platen, a long carbon ribbon connected thereto at one end along a longitudinal line on the face of the platen and 90
 adapted to be wound round the platen a number of times, means for supporting a 95
 stack of billing sheets each equipped with an engaging device at one end, suspended close to the platen, and a device connected to the platen adapted to pick up the billing sheet and interwind it with the carbon ribbon round the platen.

27. In a billing attachment for typewriters, a platen, a long carbon ribbon connected thereto at one end along a longitudinal line on the face of the platen and 100
 105 adapted to be wound round the platen a number of times, means for supporting a stack of billing sheets equipped with a fold at one of the ends, suspended close to the platen, and a fork or hook device connected 110
 to the tapes adapted to pick up the billing sheet and interwind it with the carbon ribbon round the platen.

28. In a billing attachment for typewriters, a platen, a carbon ribbon connected thereto along a longitudinal line in the periphery of the platen adapted to be wound around the platen a number of times, means for supporting a stack of billing sheets consisting of a number of forms printed one 115
 120 above the other on the sheet, and a pressure device for holding the stack with the top bill of the stack in such position that the direction of its path to the machine is toward the line on the platen along which the 125
 carbon ribbon is attached.

29. In a billing attachment for typewriters, a platen, a carbon ribbon connected thereto along a longitudinal line in the periphery of the platen adapted to be wound 130

around the platen a number of times; means for supporting a stack of billing sheets consisting of a number of forms printed one above the other on the sheet, a pressure device for holding the stack with the top bill of the stack in such position that the direction of its path to the machine is toward the line on the platen along which the carbon ribbon is attached, and means for releasing the pressure device in advance of the rotation of the platen to wind the carbon ribbon thereon.

30. In a typewriting machine, the combination of a platen, guide tapes, and means 15 separate from said tapes for automatically delivering a work sheet to the platen and into the control of said tapes.

31. In a typewriting machine, the combination of a platen, a pair of guide tapes 20 connected to said platen and co-operative with the side margins of work sheets, and means separate from said tapes for automatically delivering a work sheet to said platen and into the control of said tapes.

32. In a typewriting machine, the combination of a platen, guide tapes connected thereto and arranged to cooperate with the side margins of the work sheets, means for exerting a constant tension on said tapes, and 25 means separate from said tapes for automatically delivering work sheets to said platen and said tapes.

33. In a typewriting machine, the combination of a platen, a reproducing sheet constantly and positively connected thereto, and means for automatically delivering a work sheet to said platen and so that it may be interwound thereon with said reproducing sheet.

34. In a typewriting machine, the combination of a platen, a reproducing sheet constantly and positively connected thereto, means for exerting a constant tension on said reproducing sheet, and means for delivering a work sheet to said platen and so 45 that it may be interwound with said reproducing sheet.

35. In a typewriting machine, the combination of a platen, a reproducing sheet, 50 guide tapes, said sheet and said tapes both being connected to said platen, a support for a stack of work sheets, and a device for automatically removing a work sheet from said stack and delivering it to the platen between said reproducing sheet and said tapes.

36. In a typewriting machine, the combination of a platen, guide tapes constantly connected thereto, spring means for putting said guide tapes under tension, means 60 for delivering a work sheet to said platen and into the control of said tapes, means for rotating said platen to a predetermined extent, and releasable means for holding said platen from turning under the action 65 of said spring means.

37. In a typewriting machine, the combination of a platen, a reproducing sheet, guide tapes, said sheet and said tapes being connected to the platen and being constantly under tension, automatic means for delivering a work sheet to said platen, means for rotating said platen to a predetermined extent, and releasable means for holding said platen against the tension of said reproducing sheet and said tapes. 70

38. In a typewriting machine, the combination of a platen, tapes connected thereto, means for applying tension to said tapes, a work sheet support for a supply of work sheets in proximity to the platen, and means 80 separate from said tapes for engaging positively with said work sheets one by one and advancing them to the platen and into the control of said tapes.

39. In a typewriting machine, the combination of a platen, feeding and guiding tapes connected thereto, a support for a pile or stack of work sheets having folds at one edge, and a reciprocating element separate from said tapes and having a device for 85 engaging successively in the folds of the work sheets and advancing them into the control of the platen and the tapes.

40. In a typewriting machine, the combination of a platen, a carbon ribbon, guide 90 tapes, means for rotating the platen a predetermined number of times, said means being inoperative during further rotation of said platen in the operation of the typewriting machine, and normally locked releasing means for holding said platen against the tension of said carbon ribbon and said tapes.

41. In a typewriting machine, the combination of a platen, a device disconnected 105 from said platen for delivering an end of a billing sheet to said platen, means for rotating said platen including speed increasing gearing, and a common prime mover adapted for actuating said device and said platen rotating means in proper time relation.

42. In a typewriting machine, the combination of a platen, a sheet support, a device disconnected from said platen for 115 moving a sheet from said support to said platen, and means for turning said platen through a plurality of revolutions and coiling the sheet thereupon.

43. In a typewriting machine, the combination of a platen, a sheet support, a device disconnected from said platen for moving a sheet from said support to said platen, means for turning said platen through a plurality of revolutions and coiling the 125 sheet thereupon, and actuating means connected to both said sheet moving device and to said platen turning means.

44. In a typewriting machine, the combination of a platen, a sheet support, a de- 130

- vice for moving a sheet from said support to said platen, means for turning said platen through a plurality of revolutions and coiling the sheet thereupon, and a carbon sheet 5 connected to the platen and adapted to be interwound with said first named sheet.
45. In a typewriting machine, the combination of a platen, a sheet support, a device independent of said platen for moving 10 sheets from said support to said platen, means for turning said platen through a plurality of revolutions, and guide tapes connected to the platen and operating to coil the sheet thereupon.
- 15 46. In a typewriting machine, the combination of a platen, a sheet support, a device for moving a sheet from said support to said platen, means for turning said platen through a plurality of revolutions, guide 20 tapes connected to the platen and operating to coil said sheet thereupon, and a carbon sheet adapted to be interwound with said first named sheet.
47. In a typewriting machine, the combination of a platen, a sheet support, a device 25
- for moving a sheet from said support to said platen, means for turning said platen through a plurality of revolutions and coiling the sheet thereupon, a carbon sheet adapted to be interwound with said first 30 named sheet, and actuating means connected to both said sheet moving device and to said platen turning means.
48. In a typewriting machine, the combination of a platen, a sheet support, a device 35 for moving a sheet from said support to said platen, means for turning said platen through a plurality of revolutions, a carbon sheet connected to the platen and co-operating with said first named sheet, guide 40 tapes connected to the platen and operating to coil said first named sheet thereupon, and actuating means connected both to said sheet moving device and to said platen turning means.

In testimony that I claim the foregoing as my invention, I affix my signature this 4th day of February A. D. 1924.

EDWARD Z. LEWIS.
